G. PUCCI

CLEARER FOR DRAWING ROLLS

Filed Oct. 19, 1923

Inventor
Giacomo Pucci

By Thomas A. Jenkins Jr.

Attorney.

UNITED STATES PATENT OFFICE.

GIACOMO PUCCI, OF WESTERLY, RHODE ISLAND.

CLEARER FOR DRAWING ROLLS.

Application filed October 19, 1923. Serial No. 669,558.

To all whom it may concern:

Be it known that I, GIACOMO PUCCI, a citizen of the United States, residing at Westerly, of the county of Washington and State of Rhode Island, have invented certain new and useful Improvements in Clearers for Drawing Rolls, of which the following is a specification.

My invention relates to draft roll clearers for spinning and other textile machinery.

Where draft rolls, especially self-weighted top rolls have been employed on drawing frames, spinning frames or other textile machines, for good results in the finished product, it is essential that the rolls be kept free at all times from grease, lint, dirt, etc. Among the devices used for this purpose, cones usually made of wood and covered with flannel or cloth, have been used for many years. Where the top rolls are of different diameters, as they normally are for self-weighted top rolls, when the cone contacts the rolls of different diameters it is obvious that it will be forced to travel longitudinally thereof. However, where a single cone is employed it is necessary to turn the cone around by hand to cause it to travel in the opposite direction. I am aware that various means have been devised to automatically change the direction of travel of said cone clearer. Chief among these has been to provide a double cone having the enlarged ends of the two cones integrally joined together and provided with a shiftable weight. With this type, however, to change the direction of travel it has been necessary by means of shifting the weight, to change the inclination of said so-called integral double cone to cause first one inclined surface of the double cone to contact the rolls, and then the other after reversal. To positively and effectively shift the inclination of said clearer, ladders, gears, or other means have been employed which depend on their functioning on continued accurate alignment, which is almost impossible employing devices of this sort. So far as I am aware, I am the first to provide a cone clearer comprising a plurality of cones operated by variation in the effective weight of said respective cones alone to change the direction of travel of said clearer.

One object of my invention therefore is to provide a cone clearer comprising a plurality of cones, operated by automatic varia-

tion in the effective weight of said cones alone to change the direction of travel of said clearer.

A further object of my invention is to provide a cone clearer of the general double cone type adapted to change its direction of travel without change of inclination thereof.

A further object of my invention is to provide a cone clearer of the general double cone type of practically double the cleaning efficiency of former types as the surfaces of both cones at all times contact the rolls.

A further object of my invention is to provide a more efficient cone clearer than formerly, having one portion thereof adapted to be pulled by the other over the rolls, thus causing the pulled cone by its sliding friction on the rolls to exert a more thorough cleaning effect than has heretofore been possible.

A further object of my invention is to provide a clearer which will automatically reverse of its own mechanism, thereby obviating the necessity of building actuating members therefor on the frame end supports.

These and such other objects of my invention as may hereinafter appear will be best understood from a description of one embodiment thereof, such as is shown in the accompanying drawings in use on a drawing frame.

In the drawings, Fig. 1 is a plan view of so much of a drawing frame as is necessary to make clear the operation of my improved clearer thereon.

Fig. 2 is a front view of said frame and clearer, parts of the clearer being shown in section.

Fig. 3 is an end view of the enlarged end of one cone.

Fig. 4 is a perspective view of a suitable weight for use with my improved clearer.

In the drawings, wherein like characters of reference indicate like parts throughout, 10 are the usual frame end supports of a drawing frame. As stated, my invention is adapted for use on any type of a textile machine employing draft rolls, though for purposes of illustration I have shown a drawing frame having the top rolls of unequal diameter, the back rolls 11 being larger than the front rolls 12, which in turn are larger than the central rolls 13.

The clearer 14, comprises a plurality of

separate cones, preferably two, as shown at 15 and 16, having the enlarged ends 17 and 18 thereof adjacent each other and loosely joined together by any suitable means. The enlarged ends 17 and 18 are preferably centrally inwardly cut out to form the pockets 19 and 20 for a purpose to be described, and said cut out portions 19 and 20 are provided with the central further cored out portions 22 and 23. The cones 15 and 16 are respectively provided with the bores 25 and 26 which extend longitudinally from and which are of slightly smaller diameter than the cored out portions 22 and 23 and which extend to the contracted ends 28 and 29 of the cones 15 and 16 respectively. The balancing weights 31 and 32 are attached to said cones near the contracted ends 28 and 29 thereof, being preferably inserted in said bores 25 and 26, and secured thereto by the screws 33. Any suitable means may be employed for loosely joining together the enlarged ends 17 and 18 of the cones. In the embodiment shown, I illustrate the U-shaped hooks 34 and 35 each having one end thereof elongated as at 37 and 38, said ends extending through the bores 25 and 26 respectively for permanent attachment thereof to the balancing weights 31 and 32, preferably by means of the set screws 42. The free ends 39 and 40 of the hooks 34 and 35 may extend any distance backwards of the bores 25 and 26, or they may be dispensed with. The flat portions 43 and 44 thereof are provided with the rings 46 and 47 revolvably mounted therein. Any suitable means may be employed for joining these rings 46 and 47 and hence the cones 15 and 16 together. In the embodiment shown I employ the chain 50, though it is obvious that cord, wire or any other suitable means preferably flexible may be employed. Said cones are preferably joined together to permit slight contact of the annular portions 52 and 53, which extend around the centrally cut out portions or pockets 19 and 20, near the contacting surfaces of the cones on the rolls.

As shown, the cones are preferably covered with the flannel 55 or other like substance to which dirt, lint, etc., is apt to adhere, suitably attached to the entire conical surfaces thereof. To assist in loosening and detaching the lint, dirt, etc., between the nebs 56 of the rolls I preferably provide the brushes 57. The annular portions 52 and 53 are preferably beveled towards the outer periphery of the cones 15 and 16 as at 58, and the brushes 57 are suitably positioned at the desired intervals on the periphery of said beveled portions and extend radially outwards, from said cones, though my invention is not restricted in any respect to the use of said brushes 57.

As shown in Fig. 4, the weight 60 pref-

erably comprises a flat cylinder of slightly greater length than the central cut out portions or pockets 19 and 20 of the cones 15 and 16 respectively. In order that the weight 60 may be transferred from the pocket 19 of the cone 15 to the pocket 20 of the cone 16 free from contact with the attaching chain 50, it is preferably provided with a central bore 61. Though the embodiment described forms a convenient type of weight, it is obvious that any suitable type may be employed.

I provide means actuated by contact with the frame end support 10 movable longitudinally of said cones 15 and 16 to shift the weight from one cone to the other to change the direction of travel of said clearer 14. While any suitable means may be employed for this purpose, the preferred means shown in the embodiment comprises the cup-shaped members 65 and 66 provided with the elongated stems 67 and 68 adapted to move longitudinally within said cones 15 and 16 respectively. The cup-shaped portions 70 and 71 are adapted to be seated in and to extend longitudinally the length of the centrally cored out portions 22 and 23 of the adjacent enlarged ends 17 and 18 of the cones 15 and 16, the ends 37 and 38 and 39 and 40 of the U-shaped hooks 34 and 35 extending through suitable holes 72 therefor in the bases 75 and 76 of said cup-shaped portions 70 and 71 respectively, the flat portions 43 and 44 of the hooks 33 and 34 and bases 77 and 78 of the cored out portions 22 and 23, thus limiting longitudinal movement of the cup-shaped members 65 and 66 respectively. The elongated stems 67 and 68 thereof extend longitudinally of the bores 25 and 26 and through central bores 80 and 81 cut respectively in the balancing weights 31 and 32, beyond the contracted ends 28 and 29 of the cones. The outer ends 83 and 84 of said stems 67 and 68 are preferably slightly flattened to limit the longitudinal movement of the cup-shaped members 65 and 66 and to conveniently contact the frame end supports 10. Should the frame end supports 10 not extend high enough vertically to contact the ends 67 and 68, they may be provided with upward extensions 86 as shown in the embodiment.

The operation of my invention is obvious from the above description. The clearer 14 is rested in position on top of the top draft rolls as is usual for former types, the contracted ends 28 and 29 of the cones 15 and 16 contacting the front roll 12 and middle roll 13 and the enlarged ends 17 and 18 contacting in addition the back rolls 11. When the frame is started up all rolls revolve in one direction. Each cone will therefore revolve in the same direction and in the opposite direction to the rolls. Due,

however, to the conical shape of the cones, it is apparent that each one will tend to move longitudinally towards its contracted end, and that if the cones were of equal weight thus presenting equal friction on the rolls, the clearer 14 would remain stationary. When, however, the weight of one cone is increased, the friction of said cone against the rolls is increased, and the clearer 10 will move in one direction, the weighted cone positively driving the clearer by contact with the rolls and pulling the other cone which of itself tends to move in the opposite direction, with it backwards over the revolving rolls. It is obvious that the sliding friction of the lighter pulled cone over the rolls will exert a greater cleaning action than where positively driven by frictional contact, as so far as I am aware all the 20 contacting parts of previous types of cone cleaners have been. It is apparent, therefore, that the cleaning efficiency is more than double that of a single positively driven cone, for not only is the cleaning surface 25 of two cones presented to the rolls, but the lighter pulled cone sliding over the rolls exerts a greater cleaning effect than a single positively driven cone, as heretofore explained.

30 Referring to the drawings, as the weight 60 is shown resting in the pocket 19 of the enlarged end 17 of the cone 15, it is obvious that the clearer 14 will move towards the contracted end 28 of the weighted cone 35 15 as shown by the arrow in Fig. 2. When the clearer 14 comes to the end of its travel over the rolls, it is obvious that the enlarged end 83 of the stem 67 will contact the frame end support 10 or its extension 86. As the clearer still tends to move in the direction of arrow, it is obvious that the stem 67 and integral cup-shaped member 65 will be forced longitudinally of the cone 15 and its cup-shaped portion 70 forced against the weight 60. As soon as the weight 60 has been forced over the dead center line where the cones contact, it is obvious that it will fall into the pocket 20 of the cone 16, thereby decreasing the weight of the cone 15 and hence its frictional contact against the rolls and increasing the weight of the cone 16 and its frictional contact with the rolls. It is obvious therefore that the now heavier cone 16 will tend to move towards its contracted end 29 and drag the cone 15 after it in the opposite direction than formerly. When the clearer 14 reaches the opposite end of the frame, it is obvious that it will be similarly reversed, and so on automatically so long as the clearer is left in position on the revolving rolls.

It is obvious that I have provided a cone clearer, simple and easy to construct, and adapted to automatically reverse on the present types of draft roll machines without

building additional reversing attachments thereon and of more than double the cleaning efficiency of former types.

It is understood that my invention is not limited to the specific embodiment shown, 70 and that various deviations may be made therefrom without departing from the spirit and scope of the appended claims.

What I claim as new and desire to secure as Letters Patent is:

1. A clearer for textile machines, comprising two cones loosely attached together and adapted to travel simultaneously in one direction, and means to change the direction of travel of said clearer by varying the respective weights of said cones. 80

2. A clearer for textile machines, comprising two cones adapted to travel simultaneously in one direction and having their enlarged ends loosely joined together, a weight shiftable from one cone to the other and means movable longitudinally of said cones to shift said weight from one cone to the other to change the direction of travel of said clearer. 90

3. A clearer for textile machines, comprising two cones adapted to travel simultaneously in one direction and having their enlarged ends loosely joined together, and means to change the direction of travel of said clearer by varying the respective weights of said cones. 95

4. A clearer for textile machines, comprising two cones having pockets in their enlarged ends, said enlarged ends being loosely and flexibly joined together so as to permit the functioning surfaces of said cones to form at all times a substantially straight line, a weight shiftable from the pocket of one cone to the pocket of the other, and means longitudinally movable within said cones to shift said weight from the pocket of one cone to the pocket of the other, to vary the weight of the respective cones to change the direction of travel of said clearer. 100

105 5. A clearer for textile machines, comprising two cones each having a pocket in its enlarged end and a balancing weight at its contracted end, flexible means to loosely join the enlarged ends of said cones together, a weight shiftable from the pocket of one cone to the pocket of the other, and means to shift said weight, comprising members extending from the enlarged end of each cone and through and beyond the contracted ends of each cone and having a sufficient limited longitudinal movement to throw the weight from the pocket of one cone to the pocket of the other. 115

120 6. A clearer for textile machines, comprising two cones each having a pocket in its enlarged end and a balancing weight at its contracted end, flexible means to loosely join the enlarged ends of said cones together, a weight shiftable from the pocket of one 125 130

4
cone to the pocket of the other, and means to shift said weight, comprising members extending from the enlarged end of each cone and through and beyond the contracted end of each cone and having a sufficient limited longitudinal movement to throw the weight from the pocket of one cone to the pocket of the other, and brushes projecting radially outwards from the enlarged end of the cone.

7. A clearer device for textile machines, comprising two conical portions adapted to travel simultaneously in one direction, one portion being driven by frictional contact with the rolls to drag the other portion with sliding friction over the rolls to exert a greater cleaning effect thereon.

8. An automatically reversible clearer device for textile machines, comprising two cones adapted to travel simultaneously in one direction, and having their enlarged ends loosely joined together, one cone being driven by frictional contact with the rolls to drag the other cone with sliding friction over the rolls, and means to change the direction of travel of said clearer by varying the respective weights of said cone.

9. In a textile machine, the combination of a roll stand having draft rolls and frame end supports, a clearer for said rolls actuated by frictional contact therewith, comprising two cones adapted to travel simultaneously in one direction and having their enlarged ends loosely joined together, a weight shiftable from one cone to the other and means movable longitudinally of said cones and actuated by the frame end supports at the end of the clearer travel to shift said weight from one cone to the other to change the direction of travel of said clearer.

10. In a textile machine, the combination of a roll stand having draft rolls and frame end supports, a clearer for said rolls actuated by frictional contact therewith, comprising two cones adapted to travel simultaneously in one direction, and having their enlarged ends loosely joined together, and means actuated by the frame end supports at the end of the clearer travel to change the direction of travel of said clearer by varying the respective weights of said cones.

11. In a textile machine, the combination of a roll stand having draft rolls and frame end supports, a clearer for said rolls actuated by frictional contact therewith, comprising two cones having pockets in their enlarged ends, said enlarged ends being

loosely and flexibly joined together, so as to permit the entire conical surface of said cones at all times to contact said rolls, a weight shiftable from the pocket of one cone to the pocket of the other, and means longitudinally movable within said cones and actuated by contact with the frame end supports at the end of the clearer travel to shift said weight from the pocket of one cone to the pocket of the other, to vary the weight of the respective cones to change the direction of travel of said clearer.

12. In a textile machine, the combination of a roll stand having draft rolls and frame end supports, a clearer for said rolls actuated by frictional contact therewith, comprising two cones each having a pocket in its enlarged end and a balancing weight at its contracted end, flexible means to loosely join the enlarged ends of said cones together, a weight shiftable from the pocket of one cone to the pocket of the other, and means to shift said weight, comprising members extending from the enlarged end of each cone and to and beyond the contracted end of each cone, and having a sufficient limited longitudinal movement when brought into contact with said frame end supports at the end of the clearer travel to throw the weight from the pocket of one cone to the pocket of the other, to change the direction of travel of said clearer.

13. In a textile machine, the combination of a roll stand having draft rolls, and a clearer for said rolls, comprising two conical portions adapted to travel simultaneously in one direction, one portion being driven by frictional contact with the rolls, to drag the other portion with sliding friction over the rolls to exert a greater cleaning effect thereon.

14. In a textile machine, the combination of a roll stand having draft rolls and frame end supports, an automatically reversible clearer for said rolls, comprising two cones adapted to travel simultaneously in one direction and having their enlarged ends loosely joined together, one cone being driven by frictional contact with the rolls to drag the other cone with sliding friction over the rolls, and means actuated by contact with the frame end supports at the end of the clearer travel, to change the direction of travel of said clearer by varying the respective weights of said cones.

In testimony whereof I affix my signature.

GIACOMO PUCCI.
